UNITED STATES PATENT OFFICE

2,270,636

ILLUMINATED COMPACT

Richard Klarfield, New York, N. Y.

Application December 17, 1940, Serial No. 370,532

1 Claim. (Cl. 240—6.45)

The present invention relates to new and useful improvements in compacts and has for its primary object to provide novel means for illuminating the interior of the compact and reflecting light from the compact through a window therein to illuminate the face of a person while using the compact.

An important object of the present invention is to provide an illuminating unit for the compact which is adapted to be removed from the compact for replacement and servicing purposes, when desired.

A still further object is to provide a device of this character of simple and practical construction, which is neat and attractive in appearance, 15 relatively inexpensive to manufacture and otherwise well adapted for the purposes for which the same is intended.

Other objects and advantages reside in the details of construction and operation as more 20 fully hereinafter described and claimed, reference being had to the accompanying drawings forming part hereof, wherein like numerals refer to like parts throughout, and in which—

Figure 1 is a perspective view.

Figure 2 is a vertical sectional view.

Figure 3 is a transverse sectional view through the illuminating unit, and

Figure 4 is a diagram of the electric circuit.

Referring now to the drawings in detail, 30 wherein for the purpose of illustration I have disclosed a preferred embodiment of the invention, the numeral 5 designates the compact case which is preferably in the form of a tray which is partially closed by a top section 6 to the front edge of which is secured a lid 7 by means of a hinge 8. The under side of the lid is provided with a mirror 9.

Mounted in the tray immediately in front of the hinged edge of the lid 7 is a window 10, the 40 plane of the window being inclined forwardly as shown to advantage in Figure 2, and immediately beneath the window is a mirror 11 which is inclined in an opposite direction for reflecting the light from an electric lamp 12 which has its base portion 13 mounted in the front wall of a transversely extending tray 14 which is positioned immediately below the top section 6, said mirror 11 being inclined at such an angle as to reflect light from said electric lamp, through the window 10, forwardly and upwardly of the mirror 9 of the compact lid.

The tray member 14 is adapted for removably mounting in the rear portion of the compact tray 5 through an opening 15 formed in the side wall of the compact, the tray 14 having spring clips 16 positioned therein for clamping

a flashlight battery 17 which is connected to the lamp through the conductors 18.

The outer end wall of the tray 14 is formed with an opening 19 in which is slidably positioned a switch push-button 20 arranged with its inner end engaging a contact 21 for moving the same into engagement with the terminal 22 of the battery, whereby to energize the lamp 12 in a manner well known in the art.

The window 10 is formed in an ornamental transversely extending partition 23 mounted in the compact tray 5 which cooperates with the top 6 to provide a compartment for the removable tray 14. Positioned in the compact tray 5 immediately in advance of the partition 23 is the rack 24 for supporting the usual cosmetics, such as the lipstick 25, mascara stick 26, and also having formed therein the powder and rouge compartment 27.

From the foregoing it will be apparent that after the lid 7 has been raised the switch 20 may be actuated to energize the lamp 12 whereby the interior of the compact will be illuminated and the light reflected upon the face of a person through the window 10.

It is believed the details of construction, operation, and advantages of the device will be readily understood from the foregoing without further detailed explanation.

Having thus described the invention, what I claim is:

A compact comprising a tray having a compartment adjacent one end thereof, a lid for the tray having a mirror on the underside thereof and being hinged to the top of said compartment for opening in an upright position to expose said mirror, a window in the compartment inclining downwardly and forwardly of said mirror when the lid is swung into upright position, an illuminating device removably positioned in said compartment, said illuminating device comprising a substantially rectangular drawer having side panels, end panels and a bottom panel, a lamp socket in one of said side panels, an electric bulb mounted in said socket, spring clips mounted on said bottom panel, a battery mounted in said clips, a push button switch mounted on said bottom panel adjacent one of said end panels with the button thereof extending through said end panel, and means for electrically connecting said battery to said bulb through said switch whereby said bulb is energized by closing said switch, when the drawer is positioned in said compartment and when the drawer is out of said compartment, said mirror and said tray being adapted to reflect light from said bulb to the face of the user.

RICHARD KLEARFIELD.
